UNITED STATES PATENT OFFICE.

BRYSON D. HORTON, OF DETROIT, MICHIGAN, ASSIGNOR TO HORTON-MOREHOUSE COMPANY, OF DETROIT, MICHIGAN.

THERMAL CUT-OUT.

No. 893,586.

Specification of Letters Patent.

Patented July 14, 1908.

Application filed April 30, 1906. Serial No. 314,413.

To all whom it may concern:

Be it known that I, BRYSON D. HORTON, citizen of the United States, residing at Detroit, county of Wayne, State of Michigan, have invented a certain new and useful Improvement in Thermal Cut-Outs, and declare the following to be a full, clear, and exact description of the same, such as will enable others skilled in the art to which it pertains to make and use the same, reference being had to the accompanying drawings, which form a part of this specification.

This invention relates to thermo cut outs for electric conductors.

15 It has for its object an improved indicating device used in connection with such cut outs.

In the drawings:—Figure 1, is a longitudinal section showing the construction of a cut out of small capacity. Fig. 2, shows the invention applied with a single auxiliary wire. Fig. 3, shows the invention applied to a cut out of larger capacity. Fig. 4, is a longitudinal section of the same cut out shown in Fig. 3, but taken at right angles to the view 25 shown in Fig. 3. Fig. 5 is a longitudinal section of a modified form from that shown in Figs. 1 and 2.

Thermal cut outs (standardized in 1905 by the National Board of Fire Underwriters) of 30 capacity up to sixty (60) amperes, comprise what are known as spring clip cut outs, in which the ends of the case are capped with conducting material, and the fuse wire which runs through the case is placed in electric 35 contact with the caps. Larger cut outs or cut outs of greater capacity than sixty (60) amperes, are made with projecting blades or terminals of heavy blocks of copper, which are adapted to engage between what are 40 known as knife clips.

The invention is intended to be applied to either form, and it consists in an auxiliary wire which forms part of the conductor through the case of the cut-out, but which is 45 of very small electric carrying capacity. This auxiliary wire projects through the case and holds in confinement a plate underneath which there is a spring in a state of tension; that end of the wire which projects through 50 the confining wall and holds the plate is capable of movement when it is itself not held to prevent such movement, and upon breaking the auxiliary wire, or otherwise releasing it from its holding means, the plate held by it is 55 projected by the spring and serves as an indi-

cator to show that the holding wire has been broken. The breaking of the holding wire occurs only after the main fuse wire has been destroyed, and the plate and spring thus become an indicator to show the condition of 60 the main fuse wire.

Referring to Fig. 1, 1, indicates the walls of the case made of some non-conducting material; 2 and 3 indicate the metal caps with which the clips engage. Underneath the cap 2, and telescoping within it is a second cap 5, in electrical connection with the cap 2, and also in electrical connection with the ends of the fuse wire 6, which passes longitudinally through the case 70 and is in electrical connection with the cap 3. Between the cap 5 and the cap 2, is a chamber 8, within which chamber is located a plate 7, bearing against a spring 10 that is coiled underneath it between the plate and 75 the cap 5. This plate 7 is normally held close against the spring 10 by auxiliary wires 11, that are in electrical connection with the fuse wire 6, or the cap 3, and are also electrically secured to the plate 7, but pass through 80 holes 9, in the cap 5; these holes being large enough to allow the wire to move freely through them, but so close as to practically confine sparks and fire within the case upon disruption of the fuse.

85 The cap 2, is provided with a peep hole 13, through which the plate 7 may be inspected, and its condition noted. Preferably, on the plate there is a small boss or knob that extends into the hole 13, when the plate is projected.

In the form shown in Fig. 2, the main fuse wire 16 is secured to a holding terminal that bends slightly to one side of the center of the cap 12, and the auxiliary wire 21 passes 95 nearly centrally through the case and only a single wire is employed to hold the plate 17 against the tension of the included spring 20.

A chamber 18 is found between the cap 19 and the cap 22, but inasmuch as the plate 17 is large in this instance, and entirely covers any possible outlet for fire, the peep hole 25 may be made much larger than in the form shown in Fig. 1.

In the larger cut-outs, where the terminals 105 31 and 32 are heavy blocks of metal, these terminals project through the caps 29 and 30, and are utilized as the connecting means between the cut out and the clips. The terminals are united by the fuse wire 36 which 110

is generally in this large size, a flat strip or strips of metal with a weakening of some character intermediate its ends, so that its point of rupture will be certainly located somewhere near the middle of the case. The indicator in this character of cut-out is a plate 37, entirely external to the cut-out not included in a chamber. This plate 37 holds under compression a projectile spring 38, and is itself held by a very fine wire 33, which is drawn through the case and is soldered to the cap 30 at the point 34. The wire 33 is a part of the interior conductor of the fuse; but its carrying capacity is very slight and immediately upon the rupture of the fuse wire 33 is itself overloaded and broken.

In Fig. 5, is shown a modified form in which the indicator is made as a cup 40, which slides in tubular chamber 41; the retaining wire is carried through the diaphragm 42, which serves as an abutment for actuating spring 43, thence it is carried through the case and brought out through the same per- foration with the fuse wire 44; in assembling this form, the fuse wire is first soldered to the diaphragm 42, the cap 47 is placed over the cup, the diaphragm and the spring and the cap and diaphragm secured together by solder.

The middle case 45 is engaged in the cap 42 and cap 46 is engaged over case 45, with the fuse wire projecting through hole 49, the holding wire 48 engages through the same hole, then both fuse wire and holding wire are secured to the cap 46 by solder.

What I claim is—

1. In a thermo electric cut-out, in combination with an inclosing case, a plurality of fuse wires of unequal size extending lengthwise thereof, neither of said wires alone being capable of carrying the full strength of current intended to be passed therethrough, and a resilient indicator normally held by one of said fuse wires in retracted position with respect to the case, adapted, upon the breaking of its restraining fuse wire, to assume an abnormal position with respect to the case, substantially as described.

2. In a thermo electric cut out, in combination with a case, a movable indicator, means for actuating the indicator, a pair of electric conductors of different current-carry-

ing capacity, having a united capacity suitable to the current to be carried and each having an individual capacity less than the total current to be carried, one of said conductors being connected with the indicator and acting as a detent against the actuation thereof, substantially as described. 60

3. A thermo electric cut out, having, in combination with a case, metallic end pieces therefor, a main fuse wire extending through said case from one end piece to the other, an auxiliary wire extending loosely through one 65 of said end pieces and fixed to the other end piece, an indicator carried by the projecting end of said wire close to the exterior of the cap, and a spring engaging between the indicator and the cap whereby upon the breaking 70 of the auxiliary wire it is projected away from the cap, substantially as described.

4. A thermo electric cut out, having, in combination with a casing, a main conductor extending therethrough, an auxiliary wire 75 extending therethrough, said wire being in electrical connection with the conductor and fixed to one end of the casing with its other end projecting loosely through the other end thereof, an indicator carried on the 80 projecting end of said wire, and a spring against whose resiliency said indicator is held by said auxiliary wire against the end of the casing, adapted upon the breaking of said auxiliary wire to project said indicator away 85 from the end of the casing, substantially as described.

5. A thermo electric cut-out, having in combination a case, metallic end closure pieces therefor, a pair of fuse wires extending 90 through said casing, said wires being of unequal size, and the smaller being fixed at one end to the metallic closure and extending through the other end closure, and a resilient indicator normally held by said smaller fuse 95 wire in retracted position with respect to the end closure, adapted to be released from such position upon the disruption of said wire, substantially as described.

In testimony whereof, I sign this specification in the presence of two witnesses.

BRYSON D. HORTON.
